UNITED STATES PATENT OFFICE

CHARLES F. HAUG, OF BROOKLYN, NEW YORK, ASSIGNOR TO MASON AU & MAGEN-HEIMER CONFECTIONERY MANUFACTURING COMPANY, OF BROOKLYN, NEW YORK, A CORPORATION OF WEST VIRGINIA

DESIGN FOR A CANDY BAR

Application filed December 26, 1929. Serial No. 33,927. Term of patent 14 years.

To all whom it may concern:

Be it known that I, CHARLES F. HAUG, a citizen of the United States of America, residing in the borough of Brooklyn, county of Kings, city and State of New York, have invented a new, original, and ornamental Design for a Candy Bar, of which the following is a specification, reference being had to the accompanying drawings, forming a part thereof, in which:

Fig. 2 is an end elevation thereof.

I claim:

The ornamental design for a candy bar, as shown.

CHARLES F. HAUG.
